B. C. ROCKWELL

METHOD OF MANUFACTURING VENEERED LUMBER

Filed June 1, 1922

UNITED STATES PATENT OFFICE.

BYRD C. ROCKWELL, OF CAMDEN, ARKANSAS.

METHOD OF MANUFACTURING VENEERED LUMBER.

Application filed June 1, 1922. Serial No. 565,145.

To all whom it may concern:

Be it known that I, BYRD C. ROCKWELL, a citizen of the United States, residing at the city of Camden, county of Ouachita, and 5 State of Arkansas, have invented a certain new and useful Improvement in Methods of Manufacturing Veneered Lumber, of which the following is a full, clear, and exact description, such as will enable others skilled 10 in the art to which it appertains to make and use the same, reference being had to the accompanying drawings, forming part of this application.

My invention relates to veneered lumber 15 and the method of producing the same, and the objects of the invention are to manufacture veneered lumber by a simple and efficient method which is inexpensive and can be easily practiced.

20 Further objects of my invention are to manufacture veneered lumber in which the base or core section is formed of a cheaper grade of lumber while the face or veneered portion is formed of a high grade material, 25 preferably hardwood.

Still further objects of my invention are to initially form the base or core section in such a manner that the veneer section when applied thereto will be confined in position 30 thereon and held against displacement while the adhesive used to secure the sections together is drying.

My invention consists in the various features hereinafter set forth and illustrated in 35 the accompanying drawings, in which—

Figure 1 is a perspective detail view of a pair of core or base sections.

Figure 2 is a perspective detail view of the veneer strip or section.

40 Figure 3 is a perspective detail view of the core sections having their inner sides channeled for the reception of the veneer strip.

Figure 4 is a transverse cross-section 45 through the assembled lumber showing the veneer strip occupying the channels formed in the core strips.

Figure 5 is a longitudinal cross-section 50 through the veneering machine, and showing the assembled lumber in position thereon.

Figure 6 is a transverse section of the two core sections and the face strips ar-

ranged in the channels thereof, said face strips being formed by severing the veneer 55 strip longitudinally.

Figure 7 is a transverse cross-section of the finished veneered lumber.

This invention is an improvement on the method disclosed in the U. S. Letters Patent, 60 No. 1,394,120, granted to me on October 18, 1921.

In manufacturing veneered lumber according to my present method, two pieces or strips 10 of low grade lumber, such as 65 illustrated in Figure 1, are secured by a suitable adhesive to the opposite sides of a comparatively thin piece or strip 11 which is formed of a high grade lumber, preferably hardwood, such as quarter-sawed oak. 70 This strip 11 is slightly more than twice the thickness of the face strips when the veneered lumber is finished, so that by sawing longitudinally through the veneer strip 11 after the adhesive securing the assembled 75 strips together is set, I obtain two strips of veneered lumber each of which consists of one of the base or core pieces 10 having one side finished with the severed half of the veneer strip 11. 80

In practicing my method, each core piece 10 is formed in one of its wide flat surfaces with a comparatively shallow channel 12 which provides upwardly presented ledges or flanges 14 and 15 along the opposite edges of each core piece or section. The width of these channels 12 is such that the veneer strip 11 will fit snugly into said channel. Suitable adhesive, such as waterproof glue, is applied to each channel 90 12 or to the wide surfaces of strip 11 or to both, and the said core pieces and said veneer strip are then assembled together so that said strip occupies channels on the oppositely disposed core sections 10, as shown 95 in Figure 4. The combined depth of such channels is less than the thickness of the strip, so that when the lumber pieces are assembled, a clearance is left between the oppositely presented ledges 14 and 15. The 100 assembled lumber is then clamped together and placed under pressure in order to hold the core pieces in close contact with the veneer strip while the glue is drying.

The preferred form of machine for applying pressure to the assembled lumber is

shown in Figure 5, and is more fully disclosed in my co-pending application filed May 16, 1922, serially numbered 561,431.

This machine consists of a series of chains 5 or conveyors 17 movable longitudinally in suitable supports 18, and each of these conveyors consists of a plurality of links 19 in each of which are arranged oppositely disposed seats 20. The seats of each conveyor 10 are in transverse alignment with the corresponding seats of the other conveyors, and the assembled lumber 16 is designed to be placed transversely on said conveyors, as shown in Figure 5. The seats of each link 15 are angularly disposed relative to each other so that each pair of lumber pieces 17 will be inclined from the perpendicular; the inner or opposed side walls of each pair being inclined downwardly and inwardly 20 so as to receive at regular intervals a plurality of wedge members 21, which, when driven into position, place the assembled lumber under pressure and cause strips 11 to be held in close contact with core pieces 10. The conveyors are of the desired length 25 and are moved at a required speed so that when the links carrying the lumber reach the discharge end of the machine, the adhesive is dry, and said lumber can be safely removed from the machine without 30 danger of displacing the assembled sections 10 and 11.

After the assembled lumber piece is removed from the machine, it is sawed longitudinally through the veneer strip 11, as indicated by lines α — α in Figure 4, into halves or strips A, as shown in Figure 6, in which 11^a indicates the severed portions of strip 11. Strips A are then finished in 35 the desired form, one of such forms being shown in Figure 7 wherein grooves 22 and tongues 23 are formed in the side edges of the core sections when said strips are to be used as veneered flooring lumber. The 40 ledges 15 are of greater width than ledges 14 in order to provide sufficient stock for the formation of tongues 23.

By my improved method, I am enabled to use a veneer strip which is substantially 45 twice the thickness of the face strip of the finished lumber, thereby reducing the cost of manufacturing said face strips and eliminating the danger of breaking said strips and reducing the number of steps in the manufacture 50 of veneered lumber. The veneer strip also acts as a key strip interlocking the assembled pieces together in proper relation to each other and preventing displacement thereof while the glue is setting.

60 The severing or sawing through the veneer strip being done after the assembling and gluing operations, the veneer portion of the lumber is protected from injury during the manufacturing operations and the 65 faces of the severed veneer portions are free

from glue and in proper condition to be worked.

What I claim is:

1. The method of producing veneered lumber consisting in forming channels in the opposite sides of a pair of core sections, then securing by means of an adhesive the channel faces of said core sections to a veneer strip, the width of said strip being substantially the same as the width of the channels, then applying pressure to the sides of said core strips for a period of time, then severing the veneer strip longitudinally into two pieces each of which is secured in position in the channel of the respective core section and then finishing said core sections and said veneer portions. 75

2. The herein described method of producing veneered lumber consisting in securing by means of an adhesive a comparatively thin strip of wood to the opposite faces of a pair of core strips, then placing said assembled strips under pressure for a period of time, then removing the pressure from said assembled strips and sawing longitudinally 85 said thin strip into two face strips each of which is secured to one of said core strips. 90

3. The method of producing veneered lumber consisting in forming shallow channels in the opposite sides of a pair of core strips 95 of wood, then securing by means of an adhesive a veneer strip in position in said channels, the combined depth of said channels being less than the thickness of said veneer strip so as to provide clearance between the ledges formed by said channels, then applying pressure to the sides of said core strips, so as to bring the veneer strip in close contact with said channels, then releasing said glued strips from pressure, and 100 sawing longitudinally through the veneer strip to form two face strips, each of which is secured in the channel of the respective core strip. 105

4. The method of producing veneered lumber consisting in forming shallow channels in the opposite sides of a pair of core strips of wood, then securing by means of an adhesive a veneer strip in position in said channels, the combined depth of said channels 110 being less than the thickness of said veneer strip so as to provide clearance between the ledges formed by said channels, then applying pressure to the sides of said core strips, so as to bring the veneer strip in close contact with said channels, then releasing said glued strips from pressure and sawing longitudinally through the veneer strip to form two face strips, each of which is secured 115 in the channel of the respective core strip, 120 and forming a tongue and groove on the opposite edges of each core strip. 125

5. The method of manufacturing tongue and grooved veneered lumber consisting in forming shallow channels in the sides of two 130

core strips, then securing by means of an adhesive said strips to a veneer strip, the latter occupying the channels of said core strips, then applying pressure to the sides of the core strips while the glue is drying, then severing the veneer strip longitudinally into two face strips each of which occupies

and protrudes from the channel of the respective core strip, then forming tongues and grooves in the side edges of said core strips.

In testimony whereof I hereunto affix my signature this 27 day of May, 1922.

BYRD C. ROCKWELL.
